Application January 30, 1956, Serial No. 562,342

Claims priority, application Sweden February 3, 1955

10 Claims. (Cl. 98—38)

The present invention relates to improvements in convectors for heating rooms, of the kind which is provided in a heat chamber extending above the convector, heating being effected by blowing in fresh air through the convector.

As to this kind of convectors it is difficult to obtain a satisfactory heat transmission to the room to be heated, the said heat transmission being carried out by effecting chimney action by means of the hot air in the heat chamber. It is also known to blow fresh air through small holes at a great velocity, so-called high pressure system, air from the room being sucked with the blown-in fresh air through ejector action. In such devices the amount of air transmitted to the room is regulated through a valve on the hot water conduit or a draught valve which shuts off the air through the convector.

The invention is substantially characterized in that in an inlet for fresh air disposed below the convector there is provided a device provided with holes and rotatable in such a manner that the amount of air passing through, when the device is turned, is blown wholly or partly through the heat chamber and the convector or entirely past the said chamber and the convector, whereby the supply of heat to the room to be heated is regulated.

The invention is further characterized in that the rotatable device may consist of a roller or the like through which holes are made in one or more oblique lines in relation to the axis of rotation of the roller, so that the amount of air through the convector is continuously changed, when the roller is turned. An opening for the air of the room may be so made in a screen or the like provided in front of the heat chamber that no air flows through the convector, when the whole amount of fresh air is blown through a channel which is formed between the heat chamber and the screen.

According to the invention one or more holes may be made in a conduit provided below the heat chamber or the convector, one or more nozzles being so connected to the hole or holes, that the amount of air passing through the holes can be conveyed wholly or partly through the heat chamber with the convector or entirely past the heat chamber with the convector, by adjusting the direction of blowing of the nozzles.

In the accompanying drawing a convector according to the invention is illustrated diagrammatically. Figures 1 and 2 show the convector seen from the side, arranged for two different positions of emitting heat. Figures 3 and 4 show two different rollers and Figures 5 and 6 show another embodiment of the roller in two different positions of adjustment. Figures 7 and 8 show two other embodiments. Fig. 9 discloses the manner in which the roller of Fig. 4 is mounted in the casing for rotary movement. Fig. 10 shows a further means for rotating the roller of Fig. 1.

Referring to the drawings and particularly Fig. 1, the numeral 1 denotes a chamber or conduit for fresh air, the temperature of which may be equal to or lower or higher than the temperature in the room A for which the

2

fresh air is intended. The fresh air passes through a conduit 1b, from a central source (not shown) to the chamber 1, from which chamber the air passes through a rotatably adjustable roller 2 located in an aperture 2b. The roller is provided with holes 2a for the passage of the fresh air.

The chamber 1 defines the lower portion of a casing 3a having front wall 3b facing the room A, rear wall 3b' facing wall B of the room and two side walls 3c. At the top, the casing is provided with a grate 21. In the front wall 3b, forwardly of a common space 1a within the casing is an aperture 3 for air from the room A, which air is drawn through the casing by the ejector action of the fresh air forced through the holes 2a in the roller 2.

Above the common space 1a, the casing is divided into two vertical channels 5 and 6. A convector 4 is positioned at the lower end of the channel 5 and the portion above the convector constitutes a heat chamber which provides a chimney action. The front wall of the channel 6 is formed by wall 3b of the casing.

If the whole quantity of fresh air is blown towards the convector (Figure 1) the greatest possible emission of heat to the room is obtained. If the emission is to be reduced, the roller 2 is turned so that only some of the air passes through the convector. If the roller is turned still more, it will finally assume a position in which the air entirely passes the convector and leaves through the channel 6 between the channel 5 for the convector and the front wall 3b of the casing (Fig. 2).

When turning the roller 2 it is desirable that the air through the convector be continuously changed, both when the amount of air is legion and when there is no air. This is effected by placing the holes in the roller along one or more lines which are oblique in relation to the axis of rotation of the roller (Figure 3) or by placing the holes in zigzag fashion (Figure 4).

When the entire amount of fresh air is blown towards the channel 6, it is desirable that no air flows through the convector, whereby the transmission of heat will be as small as possible. Owing to chimney action due to the hot air in the heat chamber 5 the air tends to rise upwards through the convector. Through ejector action the air of the room is sucked through the opening 3 and a subpressure is obtained inside the opening, which subpressure will suck the air downwards through the convector. The magnitude of the subpressure depends on the ejector action and the size of the opening 3. Therefore the size of the opening 3 is so adapted that the subpressure and the chimney action neutralize each other as much as possible.

When an apparatus according to the invention is used in a room A, the amount of air must be adapted to the normal supply of ventilation. In certain cases, for example if many people are in the room, a much greater amount of fresh air is desired. In order to make this possible the roller 2 is provided partly with a series of holes with larger total area and a series of holes with smaller total area, arranged, for example in 90° in relation to these holes. When the ventilation is to be normal (Figure 5), the roller 2 is turned so that the fresh air is blown through the smaller holes 7, the larger holes 8 being shut by means of screens 9 which are secured in the casing and contact or rest against the roller and in the position shown, cover the holes 8. When the need of ventilation is great (Figure 6), the roller 2 is turned clearing the holes from the screens so that the fresh air is blown through the larger holes 8, with the smaller holes 7 then being covered by the screens.

The roller 2 is carried by a shaft 13 mounted in the walls 3c of the casing and a portion of the shaft extends beyond one of the walls as shown in Fig. 9. An operating button 14 may be fixed to the projecting portion of

the shaft 13 to turn the roller, or a lever 15 can be attached to the roller with the other end projecting through the aperture 3 in the casing to permit manipulation of the roller as in Figs. 1 and 10.

In the embodiment according to Figure 7 a nozzle 10, preferably of elastic material, is forced on the edges of the holes 2a provided in the conduit 1. By bending the nozzles 10 to the position indicated by dashed lines the fresh air can be passed entirely to the channel 6, whereby desired intermediate positions may be obtained. In order to attain a continuous change of the air through the convector the nozzles 10 can be fastened to one (or more) wall portion of the conduit 1, the said nozzles being arranged in rows forming an angle with the longitudinal axis of the conduit. The wall portion may be plane, and then the change of the supply of air is obtained by displacing the said portion, but it may be arcuate, and then the change is obtained by turning the said portion. It will be seen that a screw 17 is arranged in a window board 16 and is provided with an operating button above the window board. A rod 19 extends downwardly from the screw in the channel 6 with the lower end of the rod being connected to the nozzle by a lever 20. Manifestly, the rotation of the button will raise or lower the rod thereby moving the nozzle 10 in the proper direction.

The embodiment shown in Figure 8 has an elastic wall portion 11 attached to the conduit 1. In this case the nozzle 10 may be stiff, as the elastic portion permits change of the direction of flow of the nozzle, so that the fresh air can be successively changed from full quantity through the convector to full quantity through the channel 6.

The size of the opening 3 is so adapted that the sub-pressure inside the opening obtained through ejector action and the chimney action neutralize each other as much as possible, or the nozzles may be provided with one or more screens 12 which prevent inner circulation (Figure 8).

The following advantages are gained through the invention:

The whole motion energy of the blown-in fresh air is first of all utilized for entraining the air of the room through ejector action and secondly for increasing the transmission of heat from the convector.

By turning the roller or through the action of the nozzles a continuous regulation of the supply of heat to the room is obtained without using valves.

As the hot water conduit has no valves several convectors may be connected in series with each other. In the conduit system for hot water one tube and all the valves may be dispensed with.

The invention is not restricted to the embodiment shown and described but may be varied within the scope of the claims.

What we claim is:

1. An assemblage for heating rooms comprising a casing constituted by interconnected front, rear, side and bottom walls, partition means within the casing intermediate the front and the rear walls and extending parallel to the front and rear walls providing two channels in the upper portion of the casing with the lower ends of the channels terminating above the bottom wall, and the upper ends of the channel communicating with a room to be heated, further partition means within the casing below the lower ends of said channels and above the bottom wall and extending between said front, rear and side walls in parallelism to the bottom wall defining a common space between the further partition means and the lower ends of the two channels, a radiator arranged in the lower portion of one of the channels, means for supplying fresh air under pressure to the space formed by the bottom wall and the further partition means, the further partition means being provided with an aperture therein, air discharge means mounted in said aperture to discharge the fresh air in a stream across said common space, and to direct said stream into the lower end of either of said channels, said air discharge means including a flexible nozzle, means operatively connected with the flexible nozzle to adjust the direction of the fresh air stream, and a room air inlet in said front wall communicating with said common space whereby the room air is entrained by the stream of fresh air discharged by said flexible nozzle.

2. An assemblage as claimed in claim 1, wherein said air discharge means includes a roller having holes extending therethrough, and bearing means on the roller rotatably mounting the roller in the side walls of the casing.

3. An assemblage as claimed in claim 2, in which said holes are arranged in at least one row forming an angle with the generatrix of the roller.

4. An assemblage as claimed in claim 2, in which certain of the holes have a total cross-sectional area corresponding to a normal requirement of fresh air and other holes have a total cross-sectional area greater than that of the first-mentioned holes, the respective series of holes being disposed at an angle of 90° relative to one another so that when a greater amount of fresh air is required, the roller is rotated so that the holes of greater cross-sectional area are in communication with the common space and the means supplying fresh air.

5. An assemblage as claimed in claim 4, in which the opposite edges of the aperture of the further partition means are each provided with an arcuate screen, and each screen having an inner radius corresponding to the outer radius of the roller, with the arcuate extent of each screen being sufficient to cover the holes of greater cross-sectional area when the roller is rotated to position the holes of greater cross-sectional area opposite said arcuate screens.

6. An assemblage for heating rooms comprising a casing constituted by interconnected front, rear, side and bottom walls, partition means within the casing intermediate the front and the rear walls and extending parallel to the front and rear walls providing two channels in the upper portion of the casing with the lower ends of the channels terminating above the bottom wall, and the upper ends of the channel communicating with a room to be heated, further partition means within the casing below the lower ends of said channels and above the bottom wall and extending between said front, rear and side walls in parallelism to the bottom wall defining a common space between the further partition means and the lower ends of the two channels, a radiator arranged in the lower portion of one of the channels, means for supplying fresh air under pressure to the space formed by the bottom wall and the further partition means, the further partition means being provided with an aperture therein, air discharge means mounted in said aperture to discharge the fresh air in a stream across said common space, and to direct said stream into the lower end of either of said channels, said air discharge means including a flexible nozzle, means operatively connected with the flexible nozzle to adjust the direction of the fresh air stream, and a room air inlet in said front wall communicating with said common space whereby the room air is entrained by the stream of fresh air discharged by said flexible nozzle.

7. An assemblage as claimed in claim 6, in which said operatively connected means extends to a point exteriorly of the casing to adjust the position of the nozzle.

8. An assemblage as claimed in claim 7, in which an elastic plate is mounted across said aperture, and the nozzle is mounted on said plate.

9. An assemblage as claimed in claim 1, in which an elastic portion is mounted on said further partition means and extends over said aperture and said air discharge means is a nozzle mounted on said elastic portion whereby movement of said elastic portion determines the direction of the fresh air stream.

10. An assemblage as claimed in claim 9, in which a vertically extending plate is mounted on one side of said nozzle and being of a length sufficient to project above

said room air inlet, and at least partially into the channel containing the radiator for serving to prevent inner circulation.
